UNITED STATES PATENT OFFICE.

CONNIE E. PIZZUTOS, OF NEW YORK, N. Y.

TOWEL RACK.

Application filed July 22, 1927. Serial No. 207,723.

In apartment houses and other places, towel racks including a base and a plurality of pivotally mounted arms are usually employed, and mounted upon the wall of a room 5 in a manner that presents an unsightly appearance.

It is therefore the object of the present invention to provide a means of novel and ornamental appearance to conceal the towel and 10 supporting arms thereof from view, and at the same time permit quick and ready access to the towel or rack when desired.

More specifically stated the invention comprehends the use of a door hingedly mounted 15 on the base of the rack and adapted to normally occupy a position to conceal the arms of the rack from view, the outer side of the door being provided with an ornamental design to add to the attractiveness of the fixture and the room itself.

The nature and advantages of the invention will be better understood when the following detail description is read in connection with the accompanying drawing, the invention residing in the construction, combination and arrangement of parts as claimed.

In the drawing forming part of this application like numerals of reference indicate similar parts in the several views and where- 30 in:

Figure 1 is a view showing the normal position of the door with relation to the rack in carrying out the inventive idea.

Figure 2 is a view taken at a right angle to 35 Figure 1.

Figure 3 is a top plan view showing the rack mounted on a wall.

Referring to the drawing in detail 10 indicates the base of an ordinary towel rack, this 40 base being in the nature of an elongated member adapted to be secured vertically upon a wall of a room or any other suitable support. Forming part of the rack is a plurality of arms 11 which project at a right angle from 45 one side of the base and mounted for pivotal or swinging movement as will be readily understood.

In accordance with the present invention, I contemplate a novel and ornamental construction of means for concealing these arms 50

and the towel supported thereby from view, and thus add to the attractiveness of the room or other place in which such rack is used. To this end I contemplate the use of a door or panel 12 which may be of any suitable size 55 for the purpose intended, and may also be constructed from any suitable material and ornamental design without departing from the inventive idea. This door 12 is mounted on the base 10, adjacent one longitudinal edge 60 thereof by means of hinges of any conventional form indicated at 13 so that the door can be normally arranged in the position illustrated in Figure 1 for the purpose intended, or wholly swung to an out of the way 65 position to permit ready access to the rack as the occasion may require. While the door itself may be made in any ornamental design, the outer face of the door is preferably painted or otherwise provided with a suitable 70 ornamental design indicated at 14 which materially adds to the attractiveness of the rack in its entirety as well as the appearance of the room in which the rack is used.

While it is believed that from the foregoing description the nature and advantages of the invention will be readily apparent, I desire to have it understood that I do not limit myself to what is shown and described, and that such changes may be made when 75 desired as fall within the scope of what is claimed.

What is claimed is:

A towel rack comprising a rectangular base, means for securing said base to a wall, a 85 plurality of arms pivotally connected to said base and normally extending at right angles to said base, a screen member of approximately the same length as said base hinged to said base at one edge thereof and normally extending at right angles to said base in parallel relation to said arms to conceal said arms and the articles supported thereby and said rack being so constructed that it is open to the atmosphere upon all sides with the exception 90 of that side upon which said screen member is hinged.

In testimony whereof I affix my signature.

CONNIE E. PIZZUTOS.
